UNITED STATES PATENT OFFICE.

PETER KUZNIEWSKI, OF MILWAUKEE, WISCONSIN.

CURTAIN HOLDER.

Application filed September 16, 1921. Serial No. 501,052.

To all whom it may concern:

Be it known that I, PETER KUZNIEWSKI, a citizen of the United States, and resident of Milwaukee, in the county of Milwaukee and 5 State of Wisconsin, have invented certain new and useful Improvements in Curtain Holders; and I do hereby declare that the following is a full, clear, and exact description thereof.

10 My invention relates to a new and improved curtain holder and its object, broadly, is to provide an improved device of this kind which may be applied to a window casing or the like, without the use of screws 15 or nails or without otherwise marring the woodwork for the purpose of supporting a curtain rod and incidentally for also supporting a shade roller.

15 A further object of the invention is to provide a device of this kind which will grip the sides of the casing and may be readily adjusted to adapt it to a casing of any standard width. Another important object of the invention is to provide unitary means for 20 securing the same in its adjusted width and simultaneously secure the arm which supports the curtain rod and shade roller.

The device will be more fully understood upon reference to the accompanying drawings, in which:—

Figure 1 is a front elevation of a window casing with my invention applied thereto.

Figure 2 is a plan view of my invention applied to a casing.

35 Figure 3 is a sectional view on the line 3—3 of Figure 2, and

Figure 4 is a sectional plan view of my improved holder.

In the drawing the numeral 1 designates 40 the casing to which my invention is applied. The bracket which grips the sides of the casing is in the shape of a yoke having a web 2 on which the arms 3 and 4 are slidably mounted and which may be drawn toward 45 each other to grip the sides of the casing by means of the nuts 5 and the arm 6 is adjustably supported on the web 2 so as to extend outwardly and is provided at its outer end with a bearing 7 suitably constructed 50 for receiving one end of the curtain rod 8. A suitable slot or recess 9 is also provided intermediate the ends of the arm 6 to receive one end of a standard curtain roller.

The arms 3 and 4 are formed in the shape of an L so as to fit the front side and edge of 55 the casing and are provided with suitable spurs or gripping devices 11. The web 2 is preferably made extensible so that it may be adjusted to fit casings of different widths and, in the form which is illustrated in detail in Figures 3 and 4. One section of the web is formed in the shape of a channel 12 which slidably receives the end 13 of the other section which is polygonal in cross section. The arm 6 which is supported upon 60 the telescoping portions of these sections is secured in position thereon by means of a set screw 14 or the like. It will be seen therefore that merely by tightening the set screw the two sections of the web will be 65 secured tightly together in adjusted position and the rod supporting arm 6 will be 70 simultaneously secured. The device may then readily be applied to the casing and caused to grip the same securely by tightening one or both of the nuts 5.

It is to be noted that by the construction shown a relatively rough adjustment is secured, and the members 12 and 13 are locked in this adjustment by means of the screw 14 80 which simultaneously positions the bracket 6, and the tight gripping action of the members 3 and 4 is secured by tightening the nuts 5 upon the threaded extensions. In this manner an adequate grip on the sides of the 85 window casing is secured.

I claim as my invention:—

1. A curtain rod holder comprising a yoke of adjustable width adapted to grip opposite sides of a window casing, a curtain rod 90 bracket adjustably mounted upon said yoke, means for locking the yoke in rough adjustment and for simultaneously locking the curtain rod bracket upon said yoke, and means for effecting an accurate adjustment 95 of said yoke and for drawing the terminal portions thereof towards each other.

2. A curtain rod holder comprising a yoke of adjustable width having two overlapping portions, a curtain rod supporting member 100 adjustably clamped to said overlapping portions and adapted to bind them in rough adjusted position, said overlapping portions having screw-threaded extremities, a pair of clamping members slidably carried by 105 said screw-threaded extremities and adapted

to grip opposite sides of a window casing, and nuts carried by said screw-threaded extremities and adapted to force said clamping members into binding engagement against sides of said window casing.

In testimony that I claim the foregoing I have hereunto set my hand at Milwaukee,

in the county of Milwaukee and State of Wisconsin.

PETER ^{his} X KUZNIEWSKI.
